UNITED STATES PATENT OFFICE.

JEROME M. COLEMAN, OF WARREN, PENNSYLVANIA, ASSIGNOR TO THE ROGERS SHEAR COMPANY, OF WARREN, PENNSYLVANIA, A CORPORATION OF DELAWARE.

CORNER-BEAD.

No. 846,898.

Specification of Letters Patent.

Patented March 5, 1907.

Application filed March 15, 1906, Serial No. 306,225.

To all whom it may concern:

Be it known that I, JEROME M. COLEMAN, a citizen of the United States, residing at Warren, in the county of Warren and State of Pennsylvania, have invented new and useful Improvements in Corner-Beads, of which the following is a specification.

This invention relates to what I shall for convenience term a "corner-bead," intending by this designation to include not only the bead itself, which I shall hereinafter refer to as such, but a clip to be associated with the bead and to which lathing or equivalent means is fastened. There are ordinarily several clips used in conjunction with a bead; but whether there be one or more they are so constructed that when assembled in operative relation with the bead and when fastened to lathing or the like such bead will be held perfectly upright in a rigid manner, thereby to insure stability—a point of the utmost importance. The bead is of novel construction, and the same applies to the clip, by virtue of which these parts can be connected in such a way as to firmly lock and bind them together and prevent any possibility of the bead being accidentally wrenched off or pulled from its upright relation by carelessness on the part of a plasterer or from similar causes.

In the drawings accompanying and forming a part of this specification I show a simple form of embodiment of the invention, which to enable those skilled in the art to practice said invention I will set forth in detail in the following description, while the novelty of the invention will be included in the claims succeeding said description.

Referring to said drawings, Figure 1 is a top plan view of a corner-bead and clip connected together, each involving the invention and showing a manner of using the same. Fig. 2 is a detail view in perspective of a portion of the bead, and Fig. 3 is a like view of the clip.

Like characters refer to like parts throughout the several figures.

The bead shown in the drawings is designated in a general way by 2. This bead in practice is adapted to be located at the angle of a wall and to extend such distance from such angle that the plaster will cover the bead to its outer edge. The bead 2 may be made from any desirable material, sheet-

steel being preferably employed for the purpose, by reason of which the bead can be readily made integral. The bead 2 is so shaped as to present along its outer side longitudinally thereof a channel, as 3, and flanges, as 4, diverging from said channel, the flanges preferably having perforations 5 of any desirable number to anchor the bead firmly in place, the plaster filling these perforations. The flanges 4 have along their outer edges inturned auxiliary flanges, as 6, disposed in the present case at acute angles 65 with respect to the main flanges 4. In this way I produce a bead which is substantially tubular in form and which will be very much stiffer than one where the flanges 6 are extended outward. In addition to this I provide by such relation of the respective flanges 4 and 6 a triangular way, in which may be fitted for sliding movement the triangular head 7 of a clip, (designated in a general way by 8.) There may be several of these clips 8, connected with the bead 2, although I have illustrated only one of them in the drawings. By reason of this sliding relation the clip can be easily adjusted longitudinally of the bead. From the triangular head 7 of 75 the clip there extend divergent arms, as 9. The clip is made from a strip of resilient material, so that I can readily bend the arms 9 at different angles to each other and to adapt them to the position of the lathing. 80

It will be understood that the auxiliary flanges 6 are separated from each other, and through the space between the same the arms 9 of the clip extend in a free manner, so that the adjustment to which I have referred can be readily secured. The shape of the head 7 agrees substantially with that of the triangular space of the head bounded by the flanges 4 and 6. As the strip is resilient, it is a ready matter to adjust the same, 95 this being accomplished by moving the arms 9 toward each other, so as to free the normally solid relation of the head 7 with the flanges 4 and 6. When the arms are released, they move away from each other, so as to press the head 7 in solid engagement with the flanges 4 and 6, and thereby prevent the clip from accidentally moving. By forming the head 7 of the clip in triangular shape and fitting it in a substantially similar way 100 it will be obvious that when the clip is once

adjusted it will be held in solid relation with the bead at several places, or, in other words, the relation between the two parts will be as substantial as can be accomplished, so that when the bead is set and when the clip or clips are fastened to the lathing there is no possibility of the bead being accidentally pulled from the true position.

The flanges 4 and 6 present collectively a tubular body, the space between the flanges 6 serving as a mouth for the passage of the arms 9 of the clip. From this it will be evident that the outer portions of the sides of the body extend toward each other. These outer portions in the present case constitute the flanges 6 when the body of the bead is made in triangular form. This, however, is not essential, for I do not limit myself to any particular shape of body, although I find a body which is substantially triangular in cross-section as best adapted for my purposes. The bead therefore is composed in the present case of a body and a channel extending along the body. The clip has no movement in the channel, but moves solely in the body and fits therein when the two parts are in working relation, so that there is a bearing for a clip close to the framework upon which the plaster is laid.

What I claim is—

1. A bead having a central channel, and flanges diverging from said channel, each of the flanges having inturned flanges along

their outer edges extending toward and separated from each other.

2. A bead having a central channel, and flanges diverging from said channel, each of the flanges having inturned flanges along their outer edges extending toward and separated from each other combined with a resilient clip having a triangular head and arms, the head being adapted to longitudinally adjustably fit the space bounded by the several flanges, and the arms being adapted to extend through the space between the in-turned flanges.

3. A bead for the purpose described having a body, and a channel extending along the body, the outer portions of the sides of the body being extended toward and separated from each other to provide a mouth.

4. A bead for the purpose described comprising a substantially tubular body having a mouth along one side and a channel along the other side combined with a clip having a head to travel solely in said tubular body, said clip having arms extending from the head thereof and through said mouth.

In testimony whereof I have heretinto set my hand in presence of two subscribing witnesses.

JEROME M. COLEMAN.
